UNITED STATES PATENT OFFICE

EMMETT G. PURDY, OF DETROIT, MICHIGAN, ASSIGNOR TO DETROIT BODY DIE COMPANY, A CORPORATION OF MICHIGAN

DESIGN FOR A MOTOR VEHICLE HOOD

Application filed March 5, 1931. Serial No. 38,957. Term of patent 14 years.

To all whom it may concern:

Be it known that I, EMMETT G. PURDY, a citizen of the United States, residing at Detroit, in the county of Wayne and State of Michigan, have invented a new, original, and ornamental Design for Motor-Vehicle Hood, of which the following is a specification, reference being had to the accompanying drawings, forming part thereof.

Fig. 1 is a view in side elevation of my improved hood.

Fig. 2 is a view in perspective of the same.

What I claim is:

The ornamental design for a motor vehicle hood as shown.

EMMETT G. PURDY.
